US00D891923S

(12) **United States Design Patent** (10) Patent No.: **US D891,923 S**
(45) Date of Patent: **** Aug. 4, 2020**

(54) **CONTAINER LID**

(71) Applicant: **Yun Lin**, Huizhou (CN)

(72) Inventor: **Yun Lin**, Huizhou (CN)

(**) Term: **15 Years**

(21) Appl. No.: **29/625,709**

(22) Filed: **Nov. 12, 2017**

(51) LOC (12) Cl. **09-07**

(52) U.S. Cl.

USPC **D9/452**

(58) **Field of Classification Search**
